United States Patent Office

Des. 208,634
Patented Sept. 19, 1967

208,634

COMBINED TELEPHONE DESK SET AND TELEVISION RECEIVER OR SIMILAR ARTICLE

George M. Janda, Westchester, Ill., assignor to Automatic Electric Laboratories, Inc., Northlake, Ill., a corporation of Delaware

Filed Sept. 13, 1965, Ser. No. 87,043

Term of patent 14 years

(Cl. D26—14)

FIG. 1

FIG. 2

FIG. 3

FIG. 4

FIG. 1 is a front, left side and top perspective view of a combined telephone desk set and television receiver or similar article, showing my new design;

FIG. 2 is a right side, top and rear perspective view;

FIG. 3 is a top plan view, the broken line showing of the handset and cord being omitted for convenience of illustration; and

FIG. 4 is a right side elevational view thereof.

The dominant features of my new design are shown in solid lines in the drawings. The broken line showing of a handset and various control elements is for illustrative purposes only.

I claim:

The ornamental design for a combined telephone desk set and television receiver or similar article as shown and described.
